UNITED STATES PATENT OFFICE.

SAMUEL O. JONES, OF STILLWATER, MINNESOTA, ASSIGNOR OF ONE-HALF
TO GEORGE H. ATWOOD, OF SAME PLACE.

BICYCLE-PEDAL.

SPECIFICATION forming part of Letters Patent No. 559,385, dated May 5, 1896.

Application filed January 25, 1894. Serial No. 497,964. (No model.)

To all whom it may concern:

Be it known that I, SAMUEL O. JONES, of Stillwater, Washington county, Minnesota, have invented certain Improvements in Bi-
cycle-Pedals, of which the following is a speci-
fication.

My invention relates to improvements in foot-retaining devices for bicycle-pedals, its object being to provide a device for use in connection with bicycle-pedals which will hold the foot of the rider to the pedal, so that it will not be thrown therefrom by the strong centrifugal force generated in operating the machine, but which will allow the rider's foot to be easily removed from the pedal at the will of the rider.

My invention consists in the novel construction and combination of parts hereinafter described, and then more clearly defined by the appended claims.

In the accompanying drawings, forming part of this specification, Figure 1 is a top view of a bicycle-pedal with my plate device applied thereto. Fig. 2 is a side view of the same. Fig. 3 is a detail view of one of the end beveled spring-pins which engage the sole-plate when the foot is placed upon the pedal. Fig. 4 is a detail of the key used in clamping the sole-plate upon the shoe-sole.

My device consists of the end beveled pin 2 and its rear inwardly-pressing spring 3, both of which are seated in the cylindrical chamber 4 therefor in the foot-guard or hub 6, the hubs 6 on both sides of the pedal being similarly fitted with pins 2, so that pins are provided on each side projecting inward over the pedal. In order to prevent the turning of these pins or to lock them in restrained position in their sockets when not in use, I provide the screws 7, working through threaded horizontal holes 8 in the side of the hub and adapted to engage the side of the pin.

For use with these pins I provide the adjustable sole-plate A. This consists of the metal plates 9 and 10, having central pivotal

connection 11, and are adapted to be fastened to the foot by means of the upwardly and inwardly turned prongs 12 upon one plate, and the pronged screw-plate 13 and adjustable screw 14 upon the other plate. The screw-plate 13 is adapted to be adjusted inward or outward by means of the screw 15, (shown in dotted line,) working in the slot 16 in the plate 10, and the screw 14 can be similarly adjusted by means of the key 17. The plates can thus be fitted to any taper of shoe-sole.

The principle upon which my foot-retaining device acts is that of a retreating pin or spring, located in the pedal, which gives and then returns to engage the plate on the shoe-sole as the foot is placed upon the pedal. The shoe and plates secured thereon are adapted to be released from the catches by sliding the foot out at right angles to the catches.

Having described my invention and set forth its merits, what I claim is—

1. The combination with a bicycle-pedal, of the foot-plates centrally pivoted to each other and provided with the inwardly-turned prongs, and the screw carrying the pronged plate sustained by one of said plates at its rear end, said inwardly-turned prongs and pronged plate being adapted to secure such plates to the rider's shoe, and means for securing said plates to the pedal, substantially as and for the purposes described.

2. The combination with a bicycle-pedal, of the foot-plates pivoted together and provided with the inwardly-turned prongs to secure them to the rider's shoe, and the spring-actuated catches attached to opposite sides of the pedal and adapted to engage said plates to hold the same to the pedal, substantially as and for the purposes described.

In testimony whereof I affix my signature in presence of two witnesses.

SAMUEL O. JONES.
